UNITED STATES PATENT OFFICE

164,944

ELECTRONIC TUBE BODY

Oscar A. Pearson, Oak Park, Ill., assignor to Webster-Chicago Corporation, Chicago, Ill., a corporation of Illinois

Application September 13, 1950, Serial No. 12,173

Term of patent 7 years

(Cl. D26—8)

To all whom it may concern:

Be it known that I, Oscar A. Pearson, a citizen of the United States, residing at Oak Park, in the county of Cook and State of Illinois, have invented a new, original, and ornamental Design for an Electronic Tube Body, of which the following is a specification, reference being had to the accompanying drawing, forming part thereof, wherein:

Figure 1 is a top plan view of an electronic tube body, showing my new design;

Fig. 2 is a front elevation thereof;

Fig. 3 is an end elevation thereof; and

Fig. 4 is a top perspective view thereof.

I claim:

The ornamental design for an electronic tube body, as shown.

OSCAR A. PEARSON.
